A. D. JOHNSON ET AL

CORE REMOVING MACHINE FOR HOLLOW DRILL STEEL

Filed Nov. 9, 1923

UNITED STATES PATENT OFFICE.

ARTHUR DORMAN JOHNSON AND FREDERICK AUGUST SCHULZE, OF WELAND, ONTARIO, CANADA, ASSIGNEES TO ATLAS ALLOY STEEL CORPORATION, OF DUNKIRK, NEW YORK, A CORPORATION OF NEW YORK.

CORE-REMOVING MACHINE FOR HOLLOW-DRILL STEEL.

Application filed November 9, 1923. Serial No. 673,791.

To all whom it may concern:

Be it known that we, ARTHUR DORMAN JOHNSON and FREDERICK AUGUST SCHULZE, both citizens of the United States of America, and both residents of the town of Welland, in the county of Welland, in the Province of Ontario, Canada, have invented certain new and useful Improvements in Core-Removing Machines for Hollow-Drill Steel, 10 of which the following is the specification.

Our invention relates to core removing machines for hollow drill steel, and the object of the invention is to devise a simple means for removing the sand core from hollow 15 steel such as that which is used for rock drill purposes and it consists essentially of means for rotating the hollow steel around its longitudinal axis, means bearing against the end of the sand core for dislodging the 20 sand core, means for forcing the dislodging means longitudinally through the steel as the dislodging operation proceeds, and means for simultaneously removing the dislodged core by fluid means, as hereinafter more 25 particularly explained by the following specification.

Fig. 1 is a side elevation of our machine broken away intermediately of its length.

Fig. 2 is an enlarged sectional detail of 30 the main operating parts.

In the drawings like characters of reference indicate corresponding parts in the different views.

1 indicates a main base. 2 and 3 are supplemental bases hingedly connected to the main base at 4 and 5. 6 and 7 are two bearing standards mounted upon the main base centrally thereof. 8 is a bushing sleeve journaled freely in the bearing ends of the standards 6 and 7 and held therein by end enlargements 9 and 10. 11 is a pulley which is secured centrally upon the bushing sleeve 8 and held centrally between the standards 6 and 7 by spacing collars 12 and 13. 14 is a piece of hollow steel such as is used for rock drill purposes and containing the sand core 15. The hollow steel 14 is formed with flat faces, that is to say, in octagonal or similar form, the bushing sleeve 8 being 50 provided with correspondingly formed orifices into which the steel 14 fits. The pulley 11 is driven by suitable means and therefore when driven, revolves the steel 14 about its axis.

17 and 18 are supplemental standards in which are rotatably held bushings 19 having centre orifices corresponding in shape to the outer contour of the steel 14, thereby forming a bearing support for the ends of the steel within the bearing portions of the supplemental standards 17 and 18. The bushings 19 are held in position by end collars 20 and 21.

We will now describe the means by which the core is removed, such means being supported upon the bases 2 and 3. The mechanisms which are supported by the bases 2 and 3 are identical in character and we will therefore describe only one of these mechanisms.

22 is a standard supported upon the upper end of which is suitably mounted a T pipe 23. 24 is a tube secured at one end in the inner end of the horizontal or main arm of the T 23. 25 is a support by which the opposite end of the tube 24 is carried. 26 is an elbow secured to the extreme opposite end of the tube 24. 27 is a reducing bushing secured in the lower end of the elbow 26 and in which is secured a depending pipe 28. 29 is a depending pipe secured at its upper end in the depending arm of the T 23. 30 is an elbow secured at the lower end of the pipe 29. 31 is a pipe connecting the elbows 30 and 30*. The pipe 31 is preferably divided into two portions connected together at their adjacent ends by a valve casing 32. 33 is a fluid supply pipe provided with a fluid inlet 34 secured in the opening 35 of the casing 32. 36 is a fluid outlet provided with an outlet opening 37 extending from the casing opening 38 located at the opposite end of the casing 32 to the opening 35.

39 is a rocking shaft extending through the casing 32 provided with an operating handle 39* upon which is supported a valve disc 40 which assumes the diagonal positions indicated by full and dotted lines in Fig. 2. 41 is a small tube extending longitudinally of the tube 24 and extending intermediately of its length through a plug 42 secured in the inner end of the main arm of the T 23. The plug 42 is provided with a suitable bushing 43 through which the tube 41 extends. The inner end of the tube 41 is provided with a piston head 44 which operates longitudinally of the tube 24, its in-

ward longitudinal movement being limited by the annular shoulder 45. When it is desired to remove the sand core from the steel 14 such steel is mounted in the bushings 8 and 19 as previously described and rotated about its axis. The supplemental bases 2 and 3 are then swung into position so that the tubes 41 are in axial longitudinal alignment with the centre of the steel 14. Steam 10 or other fluid is then admitted through the pipe 33 into the valve casing 32 and is directed by the valve 40 which is in the full position shown in Figure 2, into the pipe 31, passing through such pipe into the elbow 15 30°, pipe 28, elbow 26 into the tube 24 against the outer end of the piston 44. By this means the piston 44 and the tube 41 is carried against the end of the sand core 15, the steel 14 being revolved as above described. A grinding action is produced between the inner end of the tube 41 and the sand core so that the sand core is gradually dislodged. After the dislodging operation takes place the steam or other fluid passes 20 through the centre of the tube 41 against the inner end of the sand core and passes through the crevices formed between the inner end of the tube 41 and the dislodged particles of the core so as to gradually wash 25 these particles from the end of the core and carry them outward between the tube 41 and the steel 14.

This operation continues from each end of the steel 14 until the tubes 41 meet in the 30 centre of the steel. When this operation is completed the valve 40 is swung over into the dotted position, directing the steam or other fluid into the elbow 30, pipe 29, sleeve 23 against the opposite side of the piston 44 so as to withdraw the tube 41 out of the steel. When the operation is complete the supplemental bases 2 and 3 are swung to one side so as to permit of the withdrawal 40 of the steel 14 and the insertion of a new steel.

From this description it will be seen that we have devised a very simple device whereby the sand cores of hollow steel such as that used in rock drills is quickly and easily 50 removed. It may be stated that in order to form the hollow steel above described, a steel billet or ingot is drilled or cast, giving a tubular or hollow form. The centre or hole is then filled with special sand or other 55 suitable substance after which the billet or ingot is heated to a suitable temperature and worked or rolled down to the desired size or section.

The machine hereinbefore described is 60 for the purpose of removing this sand core.

What we claim as our invention is:

1. A core removing machine comprising a support for holding a hollow steel having a sand core and in which such steel is rotatably mounted; means for rotating the hol-

low steel; means for bearing against the end of the core for dislodging the same, means for supplying fluid for carrying such dislodging means longitudinally of the hollow steel and for simultaneously removing the 70 dislodged particles as they are loosened from the core.

2. In a core removing machine, the combination with means for revolving hollow steel containing a core axially of a tube, a piston contained within the tube, an inner tube mounted within the aforesaid tube and adapted to bear at its inner end against the end of the said core, and means for supplying fluid for forcing the piston and inner tube longitudinally against the core adapted to pass through such inner tube to remove the particles of the core as they are loosened.

3. In a core removing machine, the combination with means for revolving the hollow steel containing a core around its longitudinal axis, of a main tube mounted to assume a position in longitudinal alignment with the centre of the sand core and having closed ends, an inner tube adapted to move longitudinally through the inner closed end of the main tube, a piston longitudinally movable within the main tube and secured to the outer end of the inner tube, and a valve for controlling the admission of fluid to either one side or the other of the piston.

4. In a core removing machine, the combination with means for revolving the hollow steel containing a core around its longitudinal axis, of a main tube mounted to assume a position in longitudinal alignment with the centre of the sand core and having closed ends, an inner tube adapted to move longitudinally through the inner closed end of the main tube, a piston longitudinally movable within the main tube and secured to the outer end of the inner tube, a valve casing, an inlet and outlet pipe connected to opposite sides of the casing and a pipe leading from each side of the casing substantially at right angles to the aforesaid inlet and outlet pipes adapted to communicate with each end of the main tube, and a disc valve located within the valve casing adapted to assume oppositely disposed diagonal positions across the valve casing so as to direct the fluid to either one end or the other of the main tube.

5. The combination of a cylinder, a plunger in said cylinder, a liquid projecting tube connected with said plunger and extending from one end of said plunger out of said cylinder and adapted to receive liquid from the other end of said plunger and means for supplying liquid under pressure to said cylinder to act on said plunger and to supply liquid to said projecting tube.

6. In a machine for removing cores of hollow rods, the combination of a cylinder,

a plunger in said cylinder, a liquid projecting tube secured at one end to said plunger, the other end of said tube being adapted to pass out of said cylinder, and a gland on 5 said cylinder having a bore through which said tube is adapted to pass, said gland having means for guiding said tube to said bore.

7. In a machine for removing cores of hollow rods, the combination of a means for

supporting a rod, liquid projecting tubes 10 adapted to enter the opposite ends of the rod to project jets of liquid at the core, and means actuated by the pressure of the liquid supplied to said tubes for advancing said tubes into said rod as the core is removed 15 therefrom.

ARTHUR DORMAN JOHNSON.
FREDERICK AUGUST SCHULZE.
